[57] ABSTRACT

A hinge having two leaves with a pin integral with the inner leaf, the hinge leaves having coacting semicylindrical segments nested so as to permit 180° rotation of said inner leaf relative to the outer leaf with contiguous arcuate faces of the segments being in engagement only during initial opening and final closing movements of the hinge, and said outer segment having means for engagement with the hinge pin throughout relative movement of said segments and means for engagement with the external arcuate face of the inner segment initial closing and final opening movements of the hinge.

TWO-PART HINGE WITH INTEGRAL PIN

SUMMARY OF THE INVENTION

A novel hinge of only two pieces which can be more economically manufactured, such as by extrusion, than conventional three piece hinges and which can be made integral with door frame and joint members. The leaves of the hinge have complementary semicylindrical segments adapted to nest when said hinge is in closed position as well as during initial opening and final closing movements of the hinge. A coextensive hinge pin is made integral with the outer segment during initial closing and final opening movements of the hinge. The structure of the hinge permits 180° movement thereof and any configuration of its external segment. Also, there is minimum surficial contact between the leaves of the hinge without sacrificing adequate rigidity.

BRIEF DESCRIPTION OF THE DRAWINGS

FIG. 1 is a perspective view of a hinge, in open position, constructed in accordance with the invention,

FIG. 2 is a view, similar to FIG. 3, of the hinge in closed position,

FIG. 3 is a horizontal cross-sectional view of the open hinge,

FIG. 4 is a view, similar to FIG. 3, of the closed position,

FIG. 5 is an enlarged view similar to FIG. 3, and

FIG. 6 is an enlarged view similar to FIG. 4.

DESCRIPTION OF THE PREFERRED EMBODIMENT

In the drawings, the numeral 1 designates a hinge embodying the principles of the invention and comprising a pair of hinge members or leaves 2 and 3 disposed in substantially parallel relationship. The larger or outer hinge leaf 2 may be made integral with or otherwise secured to an angular jamb member 4 which may be of the extruded type, while the smaller or inner hinge leaf 3 may be made integral with or otherwise secured to a U-shaped closure or door frame member 5 of the same type. Although illustrated, the details of construction of the jamb and door or closure members are merely typical and form no part of this invention. For purposes of illustration only, portions of a wall 6 and a door closure 7 are shown in broken lines.

It is noted that the hinge may be of any length, such as a few inches or coextensive with the contiguous margins of the door or closure and the jamb members and, preferably, has coextensive elements or parts. Also, it is pointed out that the hinge is particularly useful for mounting the swinging doors and other closures of mobile homes and recreational vehicles. A coextensive flange 8 may be made integral with the outer leaf, while the inner leaf may have a similar integral flange 9 to facilitate mounting of the leaves on the members. Even though illustrated as having three offset portions, it is readily apparent that the flange 9 may be exactly right angular.

The larger or outer leaf 2 of the hinge has an arcuate portion or substantially semicylindrical segment 10 for nesting engagement with a complementary arcuate segment or semicylindrical portion 11 of the smaller or inner hinge leaf 3 (FIGS. 2, 4 and 6) when the door is

closed. It is noted that the free or outer longitudinal margins of each of the segments is open or spaced from the remainder of said segments and that at least the contiguous portion of each of the flanges 8 and 9 extends radially of its integral segment. The outer segment 10 is of greater radius than the inner segment 11 and has an arcuate internal face 12 concentric with and complementary to the external face 15 of said inner segment. Although the external face 14 may be arcuate as shown, this is not essential except from an esthetic viewpoint; however, the arcuateness and concentricity of the internal face 13 of the internal segment is essential for guiding the pivotal movement of the inner hinge leaf relative to the outer hinge leaf.

A coextensive hinge or pivot pin 17 is disposed longitudinally and concentrically of the internal segment 11 and is integrally connected to the free end of said segment by an integral, angular, radially-extending web

19. The latter has its outer section or leg 21 stepped or offset transversely outward of its inner section or leg 23 toward, in the closed position of the hinge, an overlying angular web 16 made integral with and extending radially inward from the free end of the outer segment 10. 25 As best shown in FIGS. 5 and 6, the overlying web 16 includes an inner radial leg or section 18 connected by an intermediate transverse section or leg 20 to an outer substantially radial leg or section 22 in outward offset or stepped relationship.

30 An inner arcuate face 24, concentric with the hinge pin 17, is provided on the outer extremity of the leg 22 for coaction with said pin, and said leg has a flange 26 projecting radially outward therefrom in coacting relation to the internal arcuate face 13 of the segment 11

35 when the hinge is open as shown in FIGS. 1, 3 and 5. If desired for economy of manufacture, the entire extremity of this leg may be arcuate in plan. A lip 28 projects transversely outward from the outer end portion of the flange 26 to provide an amplified face 30 which may be arcuate and which is concentric with the segment face 13. The intermediate leg 20 has an outer portion 32 extending outwardly of the leg 22 in substantially parallel relation to its flange for coaction therewith. Preferably, an arcuate external face 34 is formed on the leg outer portion 32 and is concentric with the internal face of the segment 11. In order to prevent axial or longitudinal movement of the hinge leaves 2 and 3 relative to each other, at least one angular bracket 25 is suitably secured to the jamb member 8 adjacent the outer segment 10 and has a horizontal or transverse substantially circular arm 27 extending through aligned horizontal or transverse slots 29 in the segments 10 and 11.

50 55 When the closure or door is closed as shown in FIGS. 2, 4 and 6, the inner leaf segment 11 is nested within the outer leaf segment 10 with the faces 12 and 15 of said segments in close proximity, and with the web 19 and its sections 21 and 23 of the inner leaf 3 contiguous

60 65 the legs 18 and 22 as well as the leg 20 of the web 16 of the outer leaf 2. Upon initial opening and final closing of the door, the inner segment rotates within the outer segment with the external face 15 of said inner segment sliding over the internal face 12 of said outer segment. The hinge pin 17 of the inner leaf turns within the arcuate face 24 of the outer leg 22 of the web 16 of the outer leaf to the open position shown in FIGS. 1, 3 and

5. During approximately the last half of this opening movement as well as during approximately the first half of the closing movement of the hinge leaves, the internal face 13 of the inner segment slides over the external arcuate face 30 of the lip 28 of the flange 26 of the outer web leg 22 and the external arcuate face 34 of the outer portion 32 of the intermediate web leg 20 to guide such rotational movement in coaction with the hinge pin.

It is noted that the structure of the hinge permits opening of the door to 180° from its closed position which is particularly advantageous when the door is on a side of a vehicle. Since the hinge pin is integral with the inner leaf of the hinge, fabrication by extrusion is made possible and is more economical than conventional manufacture. Manifestly, the hinge leaves may be made integral with metal closure or door and jamb members and, when coextensive with said members, the hinge may be of extremely light-weight construction. Of course, the coextensiveness of the hinge is highly desirable from an esthetic standpoint.

The foregoing description of the invention is explanatory thereof and various changes in the size, shape and materials, as well as in the details of the illustrated construction may be made, within the scope of the appended claims, without departing from the spirit of the invention.

I claim:

1. A hinge including
a pair of substantially parallel hinge leaves adapted
to be secured to a door and a door jamb,
an outer longitudinal segment integral with one of

the hinge leaves and having an internal semicylindrical face,
an inner longitudinal segment integral with the other hinge leaf and having concentric internal and external semicylindrical faces,
the external face of the inner segment being complementary to the internal face of the outer segment for nesting therein when the hinge is closed,
a coaxial pin spaced inwardly from the internal face of said inner segment,
a substantially radial web integrally connecting the pin to the free margin of said inner segment,
an integral web projecting inwardly of said outer segment and having an internal transversely arcuate face complementary to said pin for constant mating engagement therewith,
and a pair of spaced external projections on the latter web having transversely arcuate faces complementary to the internal face of said inner segment for sliding engagement with said internal face when the hinge is in open position.

2. A hinge as defined in claim 1 wherein
the webs have inner and outer portions offset transversely of each other to provide abutments in the closed position of the hinge.

3. A hinge as defined in claim 1 wherein
the hinge leaves have integral webs for connection
with the door and door jamb,
the latter webs being contiguous when the hinge is closed and adjacent the first mentioned webs when said hinge is in open position.
